TABLE

Edmond J. Spence, New York, N. Y.

Application August 19, 1947, Serial No. 140,941

Term of patent 3½ years

(Cl. D33—14)

To all whom it may concern:

Be it known that I, Edmond J. Spence, a citizen of the United States, residing in the city of New York, county of New York, State of New York, have invented a new, original, and ornamental Design for a Table, of which the following is a specification, reference being had to the accompanying drawing, forming a part thereof.

In the drawing:

The single figure is a perspective view showing a table of my new design.

The side opposite that shown, and the rear of the table, present the same configuration as that of the front and side shown.

The characteristic feature of my table design resides in the specific ornamentation and configuration shown on the skirt element of the table.

I claim:

The ornamental design for a table, substantially as shown and described.

EDMOND J. SPENCE.
